UNITED STATES PATENT OFFICE

104,211

DESIGN FOR A HAND TRUCK

James H. Estus, Newport Beach, Calif.

Application May 6, 1936, Serial No. 62,516

Term of patent 14 years

To all whom it may concern:

Be it known that I, James H. Estus, a citizen of the United States, residing at Newport Beach, in the county of Orange and State of California, have invented a new, original, and ornamental design for a Hand Truck, of which the following is a specification, reference being had to the accompanying drawing, forming part thereof.

I claim:

The ornamental design for a hand truck as shown.

JAMES H. ESTUS.
